BROOM

Haley H. Birch, Preston, Nebr.

Application May 16, 1949, Serial No. 93,541

1 Claim. (Cl. 15—189)

1

This invention relates to brooms, and the primary object of the invention is to provide a broom embodying a head of novel construction which will stay tight on the handle and effectively withstand considerable and hard usage.

The exact nature of the invention will become apparent from the following description when considered with the accompanying drawing, in which:

The Figures 1 to 4 are fragmentary elevational views showing successive stages in the process of manufacturing a broom constructed in accordance with the present invention.

Referring in detail to the drawing, 5 indicates the usual straight elongated handle, and 6 indicates the filler of a broom head which is secured on the lower end portion of the handle. The filler 6 includes a bunch of wet coarse broom straws 7 disposed with their butt ends at the top and secured on the lower portion of the handle by winding the butt end portions of the same with wire as at 8. Smaller flat bunches of wet straws 9 are then similarly disposed and secured to opposite sides of the bunch 7 by winding the butt end portions thereof with the wire as at 10. Primary shoulder-forming bunches of wet clear straws 11 are then disposed with their butt ends down at opposite sides of the butt end portions of the bunch of straws 7 and intermediate the bunches 9, and these bunches 11 are secured in place by winding their butt ends with the wire as at 12, so as to additionally secure the bunches 9. Secondary shoulder-forming bunches of wet shorter coarse straws 13 are then disposed with their butt ends down at the outer sides of the bunches 11 but slightly higher than the latter, whereupon these bunches 13 are secured in place by winding their butt end portions with the wire as at 14 above the windings 12. The bunches 11 and 13 are then bent down over the windings 14 and temporarily held down by means of a strap or band, the bunches 11 of clear straws being at the outside of the bunches 13 of coarse straws. By using the primary and secondary shoulder-forming bunches of straws and separately winding them with wire in different spaced planes, the straws are securely fastened in place so that they will not pull out from under the wire. A staple 15 is then driven through one of the bunches 9 and the bunch 7 into the handle so as to straddle the last winding 14 and hold the wire tight, whereupon the wire is cut off to leave a short portion 16 extending beyond said staple. However, the staple 15 may be driven and the wire cut off before bending the bunches 11 and 13 down and holding them down by means of the strap or band. The butt ends of the bunches are then trimmed or cut off close to the windings 14. The partially completed broom is then taken from the winder and

2

the straws are allowed to dry. Staples 17 are driven through the other bunch 9 and the bunch 7 into the handle so as to straddle and tighten the windings 12 and 14 after drying the straws. After this, the straws are thrashed and then stitching the straws together, and trimming the lower ends of the straws. The partially completed broom is placed back on the winder to secure the exterior or finishing layer or hurl of straws to the handle, the end 16 of the wire on the filler 6 being suitably secured to the end of the wire on the winder and to the filler 6.

From the foregoing description, the nature and advantages of the invention will be apparent to those skilled in the art. Minor changes are contemplated within the spirit of the invention as claimed.

Having described the invention, what is claimed as new is:

In a broom, a handle, a bunch of straws disposed with their butt ends at the top and about the lower end portion of the handle, windings of wire securing the butt end portions of said bunch of straws on the lower end portion of the handle, flat bunches of straws at two opposite sides of the first-named bunch wired in place at the butt ends of said first-named bunch, primary shoulder-forming bunches of straws at the other two opposite sides of the first-named bunch disposed with their butt ends down at opposite sides of the butt end portions of the first-named bunch of straws, other windings of the wire securing the butt end portions of the second-named bunches in place, secondary shoulder-forming bunches of straws disposed with their butt ends down at the outer sides of but slightly higher than the butt ends of the primary shoulder-forming bunches of straws, and further windings of the wire above the first and second-named windings securing the butt end portions of the secondary shoulder-forming bunches of straws in place above and in spaced relation to the second-named windings and in engagement with said secondary bunches above said first and second-named windings, all of said shoulder-forming bunches of straws being bent down over the last-named windings.

HALEY H. BIRCH.
